CLOCK

Clarence E. Ingram and Louis T. Warriner, both of 777
N. Park Ave., Apt. 3, Pomona, Calif. 91767

Filed Sept. 30, 1971, Ser. No. 185,481

Term of patent 14 years

Int. Cl. D10—01

U.S. Cl. D42—7 D

Fig. 1

Fig. 3

Fig. 2

FIG. 1 is a front perspective view of a clock, showing my new design;

FIG. 2 is a back elevational view; and

FIG. 3 is a side elevational view, the opposite side thereof being substantially similar in appearance.

We claim:

The ornamental design for a clock, as shown.
